C. W. STEVENS,
BUILDING BOARD OR SLAB,
APPLICATION FILED OCT. 13, 1920.

1,434,509.

Patented Nov. 7, 1922.

UNITED STATES PATENT OFFICE.

CHARLES W. STEVENS, OF DETROIT, MICHIGAN.

BUILDING BOARD OR SLAB.

Application filed October 13, 1920. Serial No. 416,672.

To all whom it may concern:

Be it known that I, CHARLES W. STEVENS, a citizen of the United States, residing at Detroit, in the county of Wayne and State of Michigan, have invented certain new and useful Improvements in Building Boards or Slabs, of which the following is a specification, reference being had to the accompanying drawings.

10 The present invention aims for its purpose to provide a building board or slab constructed of any suitable plastering material preferably cement or concrete, including a requisite amount of clear sand or gravel, 15 and designed to be fastened to the outer face of a building frame in break joint fashion, so that when completing the construction of the building, the outer face will appear as though it is constructed of large stones 20 or slabs.

Another purpose is to provide a building slab or board including means to attach the slab or board to the studdings of a building frame, that is to say when surfacing the 25 sides of the frame.

A still further purpose is to provide a building slab or board, wherein a plurality of laths is embedded in one face of the board or slab, thereby not only reinforcing 30 the plastic material of the slab or board, but also affording means, whereby the board or slab may be attached to the studdings, namely to receive nails to hold the board or slab in position.

35 A further purpose is to provide a building slab or board of plastic material and laths which may be made in any proportions, or constructed in whole or half lengths.

While the design and construction at present illustrated and set forth is deemed preferable, it is obvious that as a result of a reduction of the invention to a more practical form for commercial purposes, the invention may be susceptible of changes, and the right 45 to these changes is claimed, provided they are comprehended within the scope of what is claimed.

The invention comprises further features and combination of parts, as will be herein-after set forth, shown in the drawings and claimed.

In the drawings:—

Figure 1 is a view in perspective of the improved building slab or board constructed in accordance with the invention.

Figure 2 is a cross-sectional view on line 2—2 of Figure 1.

Figure 3 is a view in elevation of a portion of a building frame, showing a plurality of building boards or slabs as applied, 60 in break joint fashion, there being some of the studs of the building projecting above the slabs.

Figure 4 is a longitudinal sectional view on line 4—4 of Figure 1.

Figure 5 is a view of the base of the mold, when the frame of the mold has been lifted.

Figure 6 is a perspective of a slab which may be cut transversely to form half sections.

Referring more especially to the drawings, 1 designates a wall of a portion of the building, and 2 denote the studdings thereof, and to which the building slabs or boards of the wall are fastened. As shown in Figure 1 each building slab or board comprises a plurality of longitudinally extending laths or strips 4. The adjacent edges of these laths are bevelled as shown at 5. The laths 4 have their ends provided with bevels 6. The bevels 5 and 6 converge in directions toward each other, so that when fastening the building slabs or boards to the studdings 2, the mortar or other pointing up plastic material may engage between the 85 outermost bevelled edges of the laths, and thereby not only securing the pointing up mortar or other plastic material in place, but also acting to hold the slabs or boards in position.

It will be noted that in constructing the building slabs or boards the laths 4 are exposed at the longitudinal and end edges of the plastic material as shown at 7 and 8, thereby affording means to receive nails or other securing means, for holding the boards or slabs to the studdings.

While the building slab or board can be constructed in various proportions, it has been found most essential to construct the 100 slab or board, so as to overlie at least three of the studdings, thereby not only reinforcing the slabs or boards more thoroughly, but also affording a building having greater strength and rigidity. The slabs or boards 105 may be constructed in half sections, so as to extend over two of the studdings, at the corners of the building, and adjacent the window and door frames.

Before applying the building boards or 110

slabs to studding, sheets of moisture or weather-proof paper, such as tar paper, or sheets of asbestos, or other like material as indicated at 9 are fastened to the studding. 5 2. After applying the moisture or weather-proof paper to the studdings, the building slabs or boards are placed in position with their longitudinal and end edges spaced as shown for the reception of pointing up mortar 10 or other plastic material, as indicated at 10, previously referred to. This pointing up mortar or plastic material engaging between the bevels of the laths or strips of the slabs or boards, not only act to hold 15 the mortar in position, but also to render the slabs or boards more rigid and secure. It will be also noted that the moisture or weather-proof paper prevents the mortar from falling entirely through the 20 spaces between the slabs or boards, as this paper is heavy and is not effected by the moisture of the plastic material or mortar.

As shown in Figure 6 a half section of building board or slab may be constructed. 25 This may be accomplished when constructing the building board or slab. For instance the laths or strips are exposed as indicated at 11 in Figure 6 so that the slab or board may be severed or sawed in half. In 30 other words the laths or strips may be cut, and as sufficient of the laths or slabs are exposed, enough of the laths or strips are allowed to project beyond the plastic material, to correspond with the projecting ends of 35 adjacent slab, so as to receive nails or other securing means to hold the half sections to the studding.

Also should it be desired to use additional securing means, the cement, concrete 40 or other plastic material may be formed with openings transversely of the center of each slab or board, while the material is in a moist condition. These openings 12, as shown in Figure 1 are arranged immediately 45 ly adjacent the laths or strips embedded in the slab, so that nails or other securing means may be inserted through the openings, and then driven through the laths. After using such additional securing means 50 the openings may be pointed up in the same manner as the spaces between the slabs are pointed up.

The building slab or board, after its completion, may appear as though it is constructed of a number of bricks. The face 55 of the slab or board may have any suitable design. For instance it may be with scroll work, or a design in imitation of stucco work, or may resemble pebble dash, or be stippled.

In order to construct half slabs or boards,

the slab during its construction may be provided with a space between end portions of the plastic material as shown at 11, so as to permit the exposed portions of the laths 65 8 to be sawed, or otherwise cut or severed centrally, in which case the laths 8 will extend beyond the plastic material, in the same manner as the laths extend on the remote ends of the slab.

The invention having been set forth, what is claimed as being useful is:—

1. As a new article of manufacture, a building slab comprising a body of set plastic material, a plurality of relatively spaced parallel laths embedded in one face of the body, the adjacent edges of the laths being undercut to insure holding the plastic material to the laths, the remote longitudinal laths having their longitudinal edges exposed to receive fastening means and also being undercut, to retain the plastic material to be used between two adjacent slabs, said laths having their ends exposed to receive fastening means, and 85 also being undercut to cooperate with the plastic material to be arranged between the adjacent ends of two slabs, the intermediate laths having fastening means passing through them, and which are adapted to 90 be driven into the studding, to hold the slab in position.

2. A wall constructed of a plurality of building slabs, each slab comprising a body of set plastic material, a plurality of relatively spaced parallel laths embedded in one face of the body, the adjacent edges of the laths being undercut to insure holding the plastic material to the laths, the remote longitudinal laths having their longitudinal edges exposed to receive fastening means and also being undercut, to retain the plastic material to be used between two adjacent slabs, said laths having their ends exposed to receive fastening means, and 100 also being undercut to cooperate with the plastic material to be arranged between the adjacent ends of the slabs, the intermediate laths having fastening means passing through them, and which are adapted to 105 be driven into the studding, to hold the slab in position, the body of the slab on its outer face having longitudinal and transverse grooves which extend to the surfaces of the laths to permit the fastening means 115 of the intermediate laths to be driven therethrough, and fillers of plastic material subsequently deposited in said grooves to cover said fastening means.

In testimony whereof I hereunto affix my 120 signature.

CHARLES W. STEVENS.
